UNITED STATES PATENT OFFICE.

ORRIN BARNES THOMPSON, OF JERSEY, OHIO.

DEVICE FOR OVERCOMING DEAD-CENTERS.

SPECIFICATION forming part of Letters Patent No. 318,831, dated May 26, 1885.

Application filed January 9, 1885. (No model.)

To all whom it may concern:

Be it known that I, ORRIN BARNES THOMPSON, a citizen of the United States, residing at Jersey, in the county of Licking and State 5 of Ohio, have invented certain new and useful Improvements in Devices for Overcoming Dead-Centers, of which the following is a full, clear, and exact description, reference being had to the accompanying drawings, forming 10 a part of this specification.

In the accompanying drawings, Figure 1 consists of a front view of my improved device applied to a fly-wheel. Fig. 2 is a sectional view of the same. Fig. 3 is a front 15 view, showing a modified form of my device. Fig. 4 is a sectional view of the modified form.

The same letters of reference are used to indicate identical parts in all the figures.

My invention relates to an improvement in 20 devices for converting rotary into reciprocating motion where a shaft is rotated by a crank and pitman; and it consists in an arm pivoted at one end to a fly-wheel or crank and held in normal position by a spring. To the other 25 end of the arm is pivoted a pitman so arranged that when the crank and pitman are in a line to produce a dead-center the force applied to the pitman moves the crank beyond the dead-center, after which the spring forces the arm 30 again to its normal position.

In the drawings I have illustrated my improvement as applied to a fly-wheel; but it is obvious that it is equally applicable to any form of crank.

35 A is an ordinary fly-wheel having its axis at B.

D is an arm pivoted to the wheel A at C. Its other end is pivoted to the pitman E at e.

F is a spring bearing against the arm D in 40 the direction opposite to the direction of the motion of the wheel or shaft. In Fig. 1 a straight spring is shown attached to the arm, and its free end resting against a pin, f, on the wheel.

45 K K are pins or stops limiting the throw of the spring or arm D, and are cushioned with a band of rubber. Any convenient form of spring may be used, the only purpose of it being to press or draw the arm D in a direc-

tion opposite to the direction of the motion of 50 the shaft.

In Figs. 3 and 4 is shown a modified form of the arm, in which it is represented attached to the shaft or crank and curved partly around the shaft, and held by the spring F. 55 Where a fly-wheel is used the arm D may be attached directly to the hub of the wheel, if more convenient. When the pitman, the axis of the shaft, and crank are in a line—that is, in a position to produce a dead-center—the 60 arm D stands at an acute angle to such line. In operation, therefore, whenever the crank, pitman, and axis are in a line to produce a dead-center the force applied to the pitman moves the arm D, as shown by the dotted 65 lines, instantly breaking the line which produced a lock or dead-center, so that the force applied to the pitman operates upon the crank to revolve the shaft. The dead-center point being passed, the spring restores the arm to 70 its normal position ready for the next half-revolution of the wheel or crank.

I do not limit myself to any form of arm or spring, the only essential being that the arm shall always stand at an acute angle to the 75 line of dead-center in which the pitman, crank, and axis of the shaft are points.

Having thus fully described my invention, I claim—

1. In a device for overcoming dead-centers in 80 any crank-movement, an arm pivoted at one end to the crank and at the other to the pitman, and pressed by a spring in a direction opposite to the direction of the motion of the shaft, and so arranged as always to stand at 85 an acute angle to the line of dead-center, substantially as described.

2. In a device for overcoming dead-centers, the arm D, pivoted at one end to the wheel or crank and at the other end to the pitman, 90 in combination with a spring and stops K K, substantially as and for the purpose described.

3. In a device for overcoming the dead-centers in a crank-movement, the pitman E, pivoted to a spring-actuated crank-arm, so that 95 power applied to the pitman moves the crank beyond the dead-center line, substantially as and for the purpose described.

4. In a device for overcoming dead-centers, a flexible crank consisting of two or more pieces or arms attached together by pivots and a spring, so that the crank may always be moved by the pitman out of the dead-center line, substantially as described.
5. In a device for preventing dead-centers, a spring-crank composed of the fly-wheel or an arm from the shaft, and the arm D, pivoted to the fly-wheel or arm from the shaft and held in place by a spring and stops, substantially as and for the purpose specified.

ORRIN BARNES THOMPSON.
